UNITED STATES PATENT OFFICE

156,411

MAGNETIC GROUNDING CONTACT CLAMP AND HOLDING DEVICE

Leonard J. Ebert, Kansas City, Mo.

Application June 4, 1949, Serial No. 3,061

Term of patent 14 years

(Cl. D26—1)

To all whom it may concern:

Be it known that I, Leonard J. Ebert, a citizen of the United States, residing in Kansas City, in the county of Jackson and State of Missouri, have invented a new, original, and ornamental Design for a Magnetic Grounding Contact Clamp and Holding Device, of which the following is a specification, reference being had to the accompanying drawing, forming a part thereof.

In the drawing—

Figure 1 is a side elevation of a magnetic grounding contact clamp and holding device, showing my new design;

Figure 2 is a plan view of the same; and

Figures 3 and 4 are end elevations showing the opposite ends, respectively, of the said clamp and holding device.

I claim:

The ornamental design for a magnetic grounding contact clamp and holding device, substantially as shown.

LEONARD J. EBERT.
